US00D671931S

(12) **United States Design Patent**
Fathollahi

(10) **Patent No.:** **US D671,931 S**
(45) **Date of Patent:** **** Dec. 4, 2012**

(54) **CASE**

(75) Inventor: **Andy Fathollahi**, Irvine, CA (US)

(73) Assignee: **Incipio Technologies, Inc.**, Irvine, CA (US)

(**) Term: **14 Years**

(21) Appl. No.: **29/404,688**

(22) Filed: **Oct. 24, 2011**

Related U.S. Application Data

(63) Continuation of application No. 29/356,692, filed on Mar. 1, 2010, now Pat. No. Des. 647,517.

(51) **LOC (9) Cl.** **14-03**

(52) **U.S. Cl.** **D14/250**

(58) **Field of Classification Search** D3/201, D3/215, 218, 269, 273, 294; D14/140, 142, D14/203.3, 217, 218, 240, 242, 250-253, D14/299, 358, 440, 450; D13/103, 107, D13/108.119; 220/4.02; 224/119, 191, 240, 224/241, 245, 682, 683; 248/309.1; 361/679.3, 361/679.56; 379/454, 455; 455/575.1, 575.6, 455/575.7, 575.8, 575.9; 190/100; 206/305, 206/320

See application file for complete search history.

(57) **CLAIM**

I claim the ornamental design for a case, as shown and described.

DESCRIPTION

FIG. 1 is a top end view of a case showing a first embodiment of our new design;

FIG. 2 is a bottom end view of the embodiment of FIG. 1;

FIG. 3 is a left side view of the embodiment of FIG. 1;

FIG. 4 is a right side view of the embodiment of FIG. 1;

FIG. 5 is a front view of the embodiment of FIG. 1;

FIG. 6 is a back view of the embodiment of FIG. 1; and,

FIG. 7 is a back perspective view of the embodiment of FIG. 1.

The broken lines in FIGS. 1-7 having a dash-dash configuration are for illustrative purposes only and form no part of the claimed design.

1 Claim, 7 Drawing Sheets
